United States Patent Office

GEORGE LAUDER, OF PITTSBURG, PENNSYLVANIA.

Letters Patent No. 65,242, dated May 28, 1867.

IMPROVED MACHINE FOR STRAIGHTENING BARS.

The Schedule referred to in these Letters Patent and making part of the same.

TO ALL WHOM IT MAY CONCERN:

Be it known that I, GEORGE LAUDER, of Pittsburg, in the county of Allegheny, and State of Pennsylvania, have invented certain new and useful improvements in Machines for Straightening Bars; and I do hereby declare that the following is a full and exact description thereof.

My invention relates to the straightening of iron, copper, or other like material by rolling it between surfaces which traverse in the same direction. The bar is treated between two rollers which are turned in the same direction, so that consequently the adjacent surfaces traverse in the opposite direction. The bar of iron is compressed between these two rollers, and is turned rapidly around by the rotation of the rollers. The axes of the rolls being properly set oblique to each other, and to the axis of the bar which is being straightened, it follows that the bar is traversed slowly along endwise, so that all portions are presented to the straightening action of the rolls, and the bar is finally delivered straight, or very nearly straight. This general mode of operation has been before known, and has been employed with some success.

My invention consists in an improved means for communicating motion to such rolls, whereby greater simplicity, and a steadier motion, and more perfect results are obtained. The accompanying drawings form a part of this specification.

Figure 1 is a side view, and

Figure 2 is an end view.

Similar letters of reference indicate like parts in both figures.

The drawings represent the novel portions, with so much of the other portions as is necessary to indicate their relation thereto.

A is the fixed framing of the machine; B and C are the straightening rolls; and B₁ C₁ are stout worm-wheels fixed on the axis thereof, in the manner represented. The bearings of the rolls may be carried in adjustable boxes; and the machine may be provided generally with all the appliances which are usual in such machines for adapting it to the different sizes and conditions of the material to be operated on. D is a cross-bar, which may be fixed to the framework, either permanently or adjustably, and which forms a support or guide for the bar which is being straightened, to prevent its descending in any contingencies below the proper level. The force of gravity will carry it down into the bite of the rolls, and the steady motion of the rolls due to my invention avoids much of the unsteadiness and tendency to agitate the bar which interferes with the success of the straightening process as usually conducted by such mechanism. E is the driving-worm. It is carried in bearings on the fixed framework A, as represented, and is driven by belting or other suitable means from a steam engine or other convenient motor. There are several threads e on the worm E, and the pitch of the several threads is properly adjusted to the pitch of the worm-wheels B₁ and C₁.

The parts being properly fitted together and lubricated, the bars may be introduced by hand, or by any suitable mechanism in the direction indicated by the red arrow, and will be carried through in the position indicated by the red outlines marked M. On being slowly discharged from the machine the bars may be received on any suitable surface, either rolling or stationary.

I do not confine myself to any specific number of threads e, or to any precise angle thereof. A single thread on the worm E would give a motion which would be very slow, unless the pitch of the thread, and consequently of the teeth or scores in the periphery of the worm-wheels B₁ C₁ were very coarse, and too great coarseness of these parts militates against the smoothness of motion which is required. I deem it very important to employ two or more threads on the worm E. It will be obvious that the worm E need not be provided with threads, except in those small portions of its length which act on the worm-wheels B₁ C₁. Quite large bars may pass through my machine without coming in contact with any surfaces except those portions of the rolls which are efficient in straightening. I do not confine myself to the employment of V-shaped threads. The shape of the threads e, and of the corresponding surfaces on the worm-wheels B₁ C₁, may be any approved form allowable, but I prefer the V-shape represented, giving by preference a square or less oblique surface on the sides of the threads which give and receive the principal strain.

Having now fully described my invention, what I claim as new therein, and desire to secure by Letters Patent, is as follows:

I claim the worm E, and worm-wheels B₁ and C₁, arranged relatively to the skewed straightening-rolls B C, and to the housing A, or its equivalent, substantially as and for the purpose herein set forth.

GEORGE LAUDER.
